UNITED STATES PATENT OFFICE.

LEE STURGES, OF ELMHURST, ILLINOIS.

DESIGN FOR A SPROCKET-WHEEL.

SPECIFICATION forming part of Design No. 28,870, dated June 14, 1898.

Application filed April 30, 1898. Serial No. 679,401. Term of patent 3½ years.

To all whom it may concern:

Be it known that I, LEE STURGES, of Elmhurst, in the county of Du Page and State of Illinois, have invented a certain new and original Design for Sprocket-Wheels, of which the following is a specification.

My novel design consists in the sprocket-wheel having the peculiar pattern or configuration of open-work, which occupies the interior of the sprocket between the rim and hub portions, as illustrated in the drawings, in which—

Figure 1 shows a side view of a sprocket wheel or gear A embodying my novel design, and Fig. 2 shows a section on line 2 2 of Fig. 1.

Five spokes or arms a radiate from the hub a', and at their outer ends each divides into two curved diverging branches a², which merge into the rim a³. Five inwardly-point-

ing somewhat spear-shaped openings B are thus provided around the center of the sprocket between the arms, and between each pair of diverging branches a² and the rim a³ is an opening C of rounded but generally triangular shape. A gracefully-curved and attractive configuration is thus produced.

I claim as my invention—

The design for a sprocket wheel or gear, substantially as shown and described.

In testimony that I claim the foregoing as my invention I affix my signature hereto, in the presence of two subscribing witnesses, this 6th day of April, A. D. 1898.

LEE STURGES.
